(**) Term: **14 Years**

(21) Appl. No.: **29/328,518**

(22) Filed: **Nov. 25, 2008**

Primary Examiner—Lisa P Lichtenstein

(74) *Attorney, Agent, or Firm*—Brian S. Steinberger; Law Offices of Brian S. Steinberger, P.A.

(57) **CLAIM**

The ornamental design for a combined ceiling fan with light, as shown and described.

DESCRIPTION

FIG. 1 is a lower front side perspective view of a combined ceiling fan with light.

FIG. 2 is an upper front side perspective view of the fan and light design of FIG. 1.

FIG. 3 is a front side view of the fan and light design of FIG. 1.

FIG. 4 is a rear side view of the fan and light design of FIG. 1.

FIG. 5 is a right side view of the fan and light design of FIG. 1.

FIG. 6 is a left side view of the fan and light design of FIG. 1.

FIG. 7 is a reduced top view of the fan and light design of FIG. 1; and,

FIG. 8 is a reduced bottom view of the fan and light design of FIG. 1.

The broken line showing of the canopy, support rod, fan blades, motor vent openings and blade end fasteners is included for the purpose of illustrating environmental structure and forms no part of the claimed design.

1 Claim, 8 Drawing Sheets
